ISAAC HILLS.
By Charles W. Rice Atty.

UNITED STATES PATENT OFFICE.

ISAAC HILLS, OF ELMHURST, ILLINOIS.

TOGGLE-HOISTING APPARATUS.

Application filed February 4, 1922. Serial No. 534,016.

To all whom it may concern:

Be it known that I, ISAAC HILLS, a citizen of the United States, and a resident of the village of Elmhurst, in the county of Du Page and State of Illinois, have invented certain new and useful Improvements in a Toggle-Hoisting Apparatus; and I do hereby declare that the following is a full, clear, and exact description of the same, reference 10 being had to the accompanying drawings, and to the numerals of reference marked thereon, which form a part of this specification.

This invention relates to a toggle hoisting apparatus and particularly to a simple, 15 easily operable apparatus which may be employed to lift heavy articles upwardly along a chain or similar member.

It is an object of the present invention to 20 provide a hoisting apparatus wherein the chain engaging means are automatically positioned.

It is also an object of this invention to provide a hoisting apparatus having resili- 25 ent means for positioning the chain engaging means and having means for automatically disengaging said chain engaging means.

It is a further object of this invention to 30 provide a hoisting apparatus of the class described, having means associated with the operating lever for limiting the movements of the chain engaging means.

It is an important object of this invention 35 to provide a hoisting apparatus which may be economically manufactured and conveniently operated, and which acts to automatically maintain the hoisted article at any desired height.

Other and further important objects of 40 this invention will be apparent from the disclosures in the specification and the accompanying drawings.

The invention (in a preferred form) is 45 illustrated in the drawings and hereinafter more fully described.

On the drawings:

Figure 1 is a side elevation showing the 50 hoisting apparatus of this invention in use.

Figure 2 is an enlarged fragmentary side elevation of a hoisting apparatus.

Figure 3 is an enlarged fragmentary section on the line 3—3 of Figure 2.

Figure 4 is an enlarged elevation with

parts in section showing the chain engaging means.

As shown on the drawings:

The hoisting apparatus of the present invention is adapted to be used to move heavy articles along a chain or similar member 1 and comprises in general a lever 2 which has pivotally secured near one end a hook 3 that is adapted to engage a sling 4 in which the load 5 is mounted. Pivoted on the lever 2 on either side of and separated a short distance from the hook 3 are chain engaging members 6 and 7 which have bifurcated hooks 8 of the construction shown in Figure 4 formed on their outer ends and adapted to be engaged over the links of the chain, the under side thereof resting on the top of the link directly below the link over which said bifurcated hook is engaged. Connected between points intermediate the ends of said chain engaging members 6 and 7 is a spring 9 which acts to draw said chain engaging members inwardly toward the spring and to pull the bifurcated hooks 8 on the ends thereof into engagement with the chain links. Stops 10, 11 and 12 are formed on the upper side of the lever 2 on the outside of the chain engaging members 6 and 7 and between said members respectively, and said stops are adapted to limit the pivotal movement of said members and said lever, the stop 12 also acting to alternately disengage said members 6 and 7 from the chain against the action of the spring 9 as the lever is lifted up and down.

In the operation of the apparatus, the hook 3 is engaged in the cradle or sling 4 in which the device to be lifted has been placed, and the chain engaging members 6 and 7 are engaged over the links of the chain in the manner indicated in Figure 2. The lever 2 is then rocked downwardly about the pivotal connection of the member 6 as a fulcrum, the stop 12 at the same time acting to disengage the chain engaging member 7 and to allow the same to move upwardly until it is pulled into the position indicated in dotted lines in Figure 2 by the action of the spring 9. The same action is then effected by lifting the lever upwardly about the pivotal connection of the member 7 as a fulcrum, the member 6 in this case being disengaged by the stop 12 and moved into engagement with the chain by the spring 9.

at a point above the dotted line position of the member 7. In each of these operations the stop 10 and 11 serve the double purpose of limiting the relative movement of the 5 chain engaging members and the lever 2 and of aiding in moving the members 6 and 7 into chain engaging position.

It will thus be apparent that I have provided an apparatus whereby the principle 10 of the lever and fulcrum may be effectively employed in the hoisting of heavy loads, and it will also be apparent that the lever may be released and the load will be maintained at any desired height.

15 While I have shown and described the apparatus herein in connection with a chain, it is of course apparent that the same might be conveniently used in connection with any other member affording means which might 20 be engaged by the hooks 8 or similar members.

The apparatus may be economically manufactured, is relatively light in weight, and can be readily adapted for a variety of uses.

I am aware that details in the construction 25 thereof may be varied through a considerable range without departing from the principle of this invention, and I therefore do not purpose limiting the patent granted otherwise than necessitated by the prior art. 30

I claim as my invention:

A mechanism of the class described comprising a lever, load supporting means thereon, a hook pivoted on the lever on each side of said load supporting means, resilient 35 means connected between the hooks, and stops on the lever between and outside the hooks.

In testimony whereof I have hereunto subscribed my name.

ISAAC HILLS.
